(57) **CLAIM**

The ornamental design for an internal divider for a container, as shown and described.

DESCRIPTION

FIG. 1 is a front perspective view of an internal divider for a container showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The even-length broken lines represent unclaimed boundaries and form no part of the claimed design. The divider is shown with a symbolic break in its length, width, and height. The appearance of any portion of the article between the break lines form no part of the claimed design.
